UNITED STATES PATENT OFFICE.

COLLIS ORMSBY, OF LOUISVILLE, KENTUCKY.

MANIFOLDING ACCOUNT DEVICE.

SPECIFICATION forming part of Letters Patent No. 696,584, dated April 1, 1902.

Application filed March 18, 1901. Serial No. 51,681. (No model.)

To all whom it may concern:

Be it known that I, COLLIS ORMSBY, a citizen of the United States, residing at Louisville, in the State of Kentucky, have invented 5 a certain new and useful Manifolding Account Device, of which the following is a specification.

My invention relates to the art of accounting; and it consists, primarily, in the construction of certain sets of files and two sets of tablets designed to fit together for simultaneous entry in duplicate, so that both sides of the paper may be used on one of the tablets, which also may be readily removed from 15 the file, while the other remains in place, and other features hereinafter set forth.

In the accompanying drawings, Figure I is a plan view of the file with the merchant's account-book thereon. Fig. II shows the customer's account-book. Fig. III is a perspective view of the two books fitted together, showing also the carbon copy-paper. Figs. IV and V are enlarged perspective views of the form of fastenings preferred.

25 In the ordinary method of keeping accounts with credit customers the items of a purchase are written in the customer's pass-book, copied in a day-book or journal, and thence posted in a large ledger kept for all customers. In a 30 device designed to avoid the possibility of errors in entry, and also to simplify the operations by providing for each customer a pass-book and also a separate account-book for each customer to be kept by the merchant, I have 35 made certain improvements to facilitate entries being made in the two books at one operation. Each of the merchant's books or tablets is on a separate file, and I use an ordinary cabinet to keep these files in regular order 40 for instant reference and use.

A suitable solid base *a* is provided, upon which are fixed a pair of posts *c* at each end for holding the carbon-copy-paper base and the customer's book and also a pair of posts 45 *d* at the side, set in line at right angles to the first pair for holding the leaves of the merchant's tablet. This latter may be a sewed booklet, or it may consist of loose leaves. It is punched with proper holes registering with 50 posts *d* and may be removed by taking out the rod *e*, which holds it loosely in place. The posts *d* may be split and notched on the

inside, so that the rod is held securely in place in the ordinary use of the tablet, but is removable when desired. The posts *c*, provided at either end, are split throughout their length, save just at the top, where they are joined together. A stiff card *j*, carrying the carbon copy-paper *h* pasted on its side, is perforated with holes registering with posts 55 *c*, and a thin rod *m* runs through the slit in said posts and is stuck through the card *j*, so that while the latter may be raised and lowered freely it may not leave the posts. The customer's tablet *f* is stitched across the top 60 and perforated with holes *g* to fit on the posts *c*. When this is in place under the first blank leaf of the merchant's tablet, it rests on the card *j*, and the carbon copy-paper is placed 65 on top of its first blank leaf and under the leaf of the merchant's tablet. When the entry is written on the latter, then a facsimile of it is copied on the customer's tablet in the proper place. Both accounts are thus kept 70 each in a separate book in regular order and 75 are necessarily duplicates of one another. The merchant's tablet leaves remain on the file until all used, and the number of pages may be the same as in the customer's book, or else they may be twice as many, and the 80 customer's book may then be written on both sides of the sheets by simply placing the said book on the posts at the opposite end of the file, as will be evident.

It sometimes occurs that a customer leaves 85 his pass-book behind. In this case the carbon-paper rests on its base-card and the entry is made just as usual. When the pass-book is next seen, a blank space will appear therein, and it may then be filled by copying from 90 the original entry.

The particular fastenings used are immaterial to my invention; but I prefer the forms shown at Figs. IV and V. The posts *d* for holding the file-leaves are split and notched, 95 as shown. The rod *e* is held thereby at any desired elevation to allow the leaves *b* free play without coming off. The posts *c*, being split, allow free play for the card *j*, carrying the carbon-paper *h* and the rod or pin *m*, and 100 prevent it from leaving the posts. It is evident that the carbon-paper may be easily removed and a new sheet substituted by withdrawing the pin *m*.

My system is distinguished from those systems wherein the merchant gives the customer a separate slip having a copy of the bill of goods on it, even when such copy is a facsimile, and also from the system wherein the customer has a book and the merchant keeps separate slips filed in order, for in both these cases there is great difficulty to assort the slips, and, furthermore, there is no fixed order of entering the items so they will occur alike on both accounts and no check in case of failure to enter on either account. Since both the items as entered and the order of entry are duplicates in my system, any possibility of disagreement is avoided, and the daily journal of sales forms at once also an individual ledger already posted.

Having thus described my invention and its use, what I claim, and desire to secure by Letters Patent, is the following:

1. The combination in an accounting device, of a rigid file-base having two sets of posts set in lines at right angles to each other, a merchant's file-book detachably retained on one of said sets of posts, a removable customer's book with perforations fitting over the other of the sets of posts so as to interfold with the other book, and a card carrying a sheet of carbon-paper attached at one side 30 and held to loosely slide on the latter posts, the carbon-paper interfolding with the books so that the writing on the merchant's file-book may be copied in facsimile in the removable customer's book.
2. The combination of a set of customer's pass-books perforated at one end, with a set of files carrying each a merchant's book removably fastened on a set of posts, said file having a set of posts in a line at right angles 40 to the first set to support the customer's book

and loosely carrying a card having a carbon-sheet attached at one side thereof, for the purpose set forth.

3. The combination of a pass-book perforated at one end, a file carrying a book removably held on posts at one side thereof, and having at each end a pair of slotted posts either pair of which may hold the pass-book loosely in place and a card loosely fastened to slide on one pair of said end posts, held thereon by a pin and having a carbon-sheet interfolding with the leaves of the said books.

4. An account-tablet comprising a base having at each end a pair of slotted posts and at one side a pair of posts split and notched inside, a book perforated at the side to register with said posts, means for holding said book in place, and a card carrying a sheet of carbon-paper and having holes registering with either of the two sets of end posts and held loosely thereon by a pin playing freely in the slits thereof.

5. In an accounting device a file comprising a base having a set of end posts split to allow free play of a pin therein, a second set placed in line at right angles to the first set and slotted and notched on the inside to hold a rod therein at different elevations, in combination with a card carrying a sheet of carbon-paper and perforated and fitting on the 70 said end posts of the file-base and held loosely thereon by a pin, as described.

In testimony whereof I have hereunto set my name in the presence of the two subscribed witnesses.

COLLIS ORMSBY.
